UNITED STATES PATENT OFFICE.

ANDREW V. RYDER, OF BELLEVUE, OHIO, ASSIGNOR TO EDITH RYDER,
OF BELLEVUE, OHIO.

CULTIVATOR-COUPING.

SPECIFICATION forming part of Letters Patent No. 752,594, dated February 16, 1904.

Application filed September 3, 1903. Serial No. 171,748. (No model.)

To all whom it may concern:

Be it known that I, ANDREW V. RYDER, a citizen of the United States, residing at Bellevue, in the county of Huron and State of Ohio, have 5 invented certain new and useful Improvements in Cultivator-Couplings; and I do declare the following to be a full, clear, and exact description of the invention, such as will enable others skilled in the art to which it appertains to 10 make and use the same.

My invention is an improved coupling for coupling the draw-bar of a cultivator-beam to the transverse supporting-bar of the cultivator-frame and to admit of the cultivator-beam 15 being adjusted both laterally and vertically; and my invention consists in the construction, arrangement, and combination of devices hereinafter described and claimed.

In the accompanying drawings, Figure 1 is 20 a perspective view of a portion of a sulky-cultivator provided with my improved coupling. Fig. 2 is a detail perspective view of my improved cultivator-coupling. Fig. 3 is a horizontal sectional view of the same, taken on 25 the plane indicated by the line *a a* of Fig. 2. Fig. 4 is a vertical sectional view of the same, taken on the plane indicated by the line *b b* of Fig. 2.

In Fig. 1 of the drawings, which illustrates 30 a portion of a sulky-cultivator of ordinary construction, the transversely-disposed supporting-bar, to which the draft-rods of the cultivator-beams are connected, is indicated at 1, the cultivator-beams are indicated at 2, and 35 their respective draw-bars are indicated at 3 and have their front portions upturned vertically, as at 4.

My improved couplings are adapted for connecting the said upturned front ends of the 40 draw-bars to the supporting-bar, so that the cultivator-beams are adapted to be laterally adjusted on the supporting-bar to widen or narrow the space between the cultivator-beams, according to the width of the spaces between 45 the rows of corn, and the said couplings are also adapted to permit of the vertical adjustment of the draw-bars and cultivator-beams to regulate the depth to which the cultivator shovels or points penetrate the earth when in

operation. I will now describe one of my said 50 improved cultivator-couplings, which is shown in detail in Figs. 2, 3, and 4 of the drawings.

The body 5 of the coupling, which in practice is preferably a malleable casting, is provided on one side with a pair of cylindrical 55 sleeves 6, which are horizontally disposed in line with each other and the inner ends of which are suitably spaced apart, as at 7. These sleeves are split on their rear sides from end to end, as at 8, and are provided at their 60 inner ends with rearwardly-extending lugs 9. A pair of lugs is thus provided for each of the said cylindrical split sleeves, and the said pairs of lugs are connected together by clamping-bolts 10. The cross-bar or supporting- 65 bar of the cultivator passes through the said sleeve 6 and the coupling is adjustable longitudinally on the said cross or supporting bar and is hence adjustable laterally with respect to the cultivator-frame and to the next adjacent coupling on the said supporting or cross bar. 70

To secure the coupling at any desired adjustment on the cross-bar, I provide a split collar 11, which is also disposed on the cross-bar and in the space 7 between the inner ends of the said sleeves and is provided at its projecting ends with a clamping-bolt by means of which it may be securely clamped. It will be 75 understood that the bolts 10, with which the sleeves 6 are provided, enable the said sleeves to be contracted readily from time to time, as may be required, to take up the wear on the cross-bar. It will also be understood that the said sleeves effect a pivotal connection between 80 the coupling and the cultivator cross-bar, so that the coupling is movable angularly in a vertical plane thereon. 85

On the front side and at the center of the body 5 of my improved coupling are formed 90 a pair of vertically-disposed cylindrical split sleeves 13, which are perpendicular to the sleeves 6 and are similar in construction thereto. The lugs 14 of the sleeves 13 are connected together in pairs by clamping-bolts 15, and the 95 inner ends of the said sleeves are appropriately spaced apart, as at 16. The vertical portion of the cultivator-beam draw-bar extends

through the vertically-disposed split sleeves 13 and is vertically adjustable therein. The bolts 15, in connection with the peculiar construction of the split sleeves 13, enable the latter to be compressed readily, as may be required, to take up the wear of the said draw-bar, and the latter is maintained at any required vertical adjustment in the coupling by means of a split collar 17, which is similar in construction to the collar 11, hereinbefore described, is clamped on the vertical portion of the draw-bar by the bolt 18, and is disposed in the space 16 between the inner ends of said split sleeves 13.

15 From the foregoing description, taken in connection with the accompanying drawings, the construction and operation of the invention will be readily understood without requiring a more extended explanation.

20 Various changes in the form, proportion, and the minor details of construction may be resorted to without departing from the principle or sacrificing any of the advantages of this invention.

25 Having thus fully described my invention, what I claim as new, and desire to secure by Letters Patent, is—

1. A cultivator-coupling of the class de-

scribed, having a pair of horizontally-disposed clamping-sleeves to engage the cross-bar of a 30 cultivator and having a pair of perpendicularly-disposed clamping-sleeves to engage the vertical portion of a cultivator-beam draw-bar.

2. A cultivator-coupling of the class described, having a pair of horizontally-disposed 35 split clamping-sleeves to engage the cross-bar of a cultivator, a pair of perpendicularly-disposed split clamping-sleeves to engage the perpendicular portion of the cultivator-beam draw-bar, and means to contract said clamping-sleeves on said cross-bar and cultivator-beam draw-bar.

3. A coupling of the class described, having a pair of sleeves spaced apart and adapted to engage and slide upon an element of a cultivator, and a clamping-collar on said element 45 of the cultivator and disposed in the space between said sleeves to secure the coupling when adjusted on said cultivator element.

In testimony whereof I have hereunto set my 50 hand in presence of two subscribing witnesses.

ANDREW V. RYDER.
